Charles Chinnoch, of New York, N.Y.
Letters Patent No. 550 - Dated Apr. 19th 1853.

The schedule referred to in these Letters Patent and making part of the same
To all whom it may concern:

Be it known, that I, Charles Chinnoch, of the City,
County and State of New York, have invented or produced a new and original design

for Cast Metal Fronts of Clock-cases, and I do hereby declare that the following is a full and exact description of the same, reference being had to the accompanying drawings forming part of this specification, in which

Fig: 1. is a front elevation

Fig: 2. is a side elevation

Fig: 3. is a vertical section through the centre.

Fig: 4. is a horizontal section in the line 1,2. of Fig. 1.

Fig: 5. is a horizontal section in the line 3,4. of Fig: 1, and

Fig: 6. is a horizontal section in the line 5,6. of Fig: 1.

Similar letters of reference indicate corresponding parts in the several Figs.

This design consists of a single plate of nearly uniform thickness throughout. The centre part surrounding the opening, A, for the clock face, and the opening, B, for the adjustment of the pendulum, is flat, and surrounded by an ornamental frame or border whose sides C, C, are parallel on their inner edges, a, which terminate in an arch b, over the opening, A, and whose bottom part is square on its inner edge, c, with the sides, a, except where it is received in the form of an inverted arch d, below the opening B. The profiles and sections of the border are well shown in the drawings which illustrate their form. Its lower part forms a pediment and the whole is supported by two scroll and claw feet, D, which form the termination of the lower corners.

What I claim as my invention or production, is The design & configuration of the plate shown in the drawings and described, forming the front of a clock case.
